UNITED STATES PATENT OFFICE.

JOSEPH A. ROURKE, OF BOSTON, MASSACHUSETTS.

COMPRESSION-HYDRANT.

1,176,855.

Specification of Letters Patent. Patented Mar. 28, 1916.

Application filed September 19, 1912. Serial No. 721,162.

To all whom it may concern:

Be it known that I, JOSEPH A. ROURKE, a citizen of the United States, residing at Boston, in the county of Suffolk and State of Massachusetts, have invented certain new and useful Improvements in Compression-Hydrants; and I do hereby declare the following to be a full, clear, and exact description of the invention, such as will enable others skilled in the art to which it app pertains to make and use the same.

The present invention relates to hydrants and more particularly to fire hydrants of the compression type.

The object of the invention is to provide an improved closure for the valve mechanism and make certain other improvements in the construction and arrangement of the parts of a hydrant of this type causing a resultant increase in efficiency.

With this object in view, the various features of the invention consist in certain novel features of construction, combinations and arrangements of parts hereinafter described and claimed, the advantages of which will be obvious to those skilled in the art from the following description.

In the accompanying drawings illustrating the preferred form of the invention, Fig. 1 is a longitudinal section in elevation of a portion of a hydrant, showing the several features of the invention in their preferred form; Fig. 2 is a transverse section taken upon the line 2—2 of Fig. 1; Fig. 3 is a detail view showing a section taken upon the line 3—3 of Fig. 1; Fig. 4 is a top plan view of the hydrant with the hood applied thereto; and Fig. 5 is an elevation of the hydrant showing the hood secured in position.

The illustrated embodiment of the invention is shown in connection with a hydrant of the type described in the application filed by Rourke, April 6, 1912, Serial No. 689,036.

This hydrant is provided with a main valve casing 1, a stand pipe or barrel 2 and a head 3 which carries the hose nozzles 4 and the main valve operating mechanism. The main valve 5 is rigidly secured to the lower end of a spindle 6 and is arranged to engage the valve seat 7. The upper end of the valve spindle is threaded to engage an operating nut 10 which is journaled in the upper portion of the head and held against longitudinal movement relative thereto.

The valve spindle is held against rotation and when the operating nut is rotated the

spindle is moved axially to open and close the valve. With this construction and arrangement a substantially unobstructed water way or passage 12 is provided having a series of diverging passages 13 at its upper end connecting with each of the hose nozzles 4. In order to equalize the pressure upon opposite sides of the main valve prior to opening the same, a by-pass is provided which is actuated by an operating rod 15 having a polygonal operating nut 16 secured to its upper end.

It is very desirable that the operator should know at all times the exact position of the main valve and to this end an indicating member 17 is secured to the valve spindle 6 and is arranged to move along the face of the standard 18 which is provided with suitable indications to show the position of the valve. In the illustrated embodiment of the invention this indicating device, as shown clearly in Fig. 3, consists of a pair of metal straps 19 secured together at their inner ends adjacent to the valve spindle and having their outer free ends extended in opposite directions and bent laterally to position them parallel to the indicating faces of the standards. In addition, proper indicating characters are applied to the spindles for controlling both the main valve and the hose nozzles to show the proper direction which the spindle should turn to open or close the valve.

It is very desirable in hydrants of this type that a simple and efficient closure shall be provided to entirely cover and protect the operating mechanism for the valve and other exposed portions of the hydrant and that this closure may be firmly secured in place to prevent tampering with the valve when the hydrant is not in use. To this end a hood 20 is provided with its lower edge resting at a plurality of points upon a ledge 21 formed integral with the head 3. The hood 20 is provided with a bifurcated foot 22 which embraces the operating rod 15 and the hood is locked in position by a lateral projection 23 secured to the rod and extending over the foot when the by-pass is closed, as described clearly in the application above referred to. In addition, the hood is securely clamped to the head of the hydrant by a clamping member 25 which is loosely supported in the upper portion of the hood 20 and is arranged to operatively engage with a co-operating clamping ring 26 thread-

edly secured in the standard 18. The clamping ring 26 is provided with a plurality of inturned flanges 27 having their lower faces tapered and engaged by outturned feet 28 formed upon the clamping member 25, as shown clearly in Fig. 2. The upper portion of the clamping member is provided with a polygonal nut 30 to enable the member to be readily rotated to move the feet 28 beneath the flanges 27, forcing the hood firmly upon the head 3. In order to force the hood yieldingly into engagement with the head 3 and avoid any rattling or chattering of the hood, a flexible washer 31 is interposed between 15 the coöperating faces of the clamping member and hood. The clamping member is normally retained in position in the upper portion of the hood, but in order to permit the removal thereof a plurality of recesses 20 32 are formed in the hood and arranged to register in one position with the outturned feet 28 to allow the clamping member to be removed. When applying the hood it is desirable that means shall be provided for positioning and guiding the hood properly to not only facilitate the application of the hood but to prevent injury and possible breakage to the projecting parts of the valve mechanism by coming in contact with the 25 edges of the hood. To this end the hood is formed as shown in Fig. 2 with a pair of oppositely disposed ribs 35 which engage with coöperating guideways formed in guide pieces 36. These guide pieces are provided 30 with extended upper faces located above the nozzles and if the hood is applied in the wrong position the lower edge will contact with the face of the guide piece and do no injury to the valve. In addition, the provision of the guides serves to facilitate the 35 application of the hood to the hydrant as the operator can readily determine the exact position in which the hood should be placed to fit properly upon the head.

40 45 While it is preferred to employ the specific construction and arrangement of parts shown and described, it will be understood that this construction and arrangement is not essential except so far as specified in the claims, and may be changed or modified 50 without departing from the broader features of the invention.

The invention having been described, what is claimed is:—

55 1. A hydrant having, in combination, a main valve, an operating spindle for the valve, mechanism for actuating the spindle to open and close the valve, a hood inclosing

the spindle and actuating mechanism, a 60 clamping member loosely supported and retained upon the hood, and a fixed clamping ring coöperating with the clamping member to lock the hood in position upon a partial rotation of the member.

2. A hydrant having, in combination, a 65 stand pipe, a main valve, an operating spindle for the valve extending up through the stand pipe, mechanism for actuating the spindle, a plurality of hose nozzles supported upon the upper portion of the stand pipe, 70 a hood inclosing the valve actuating mechanism and hose nozzles, a clamping member loosely supported and retained upon the hood, and means mounted upon the stand pipe and coöperating with the clamping 75 member to lock the hood in position upon a rotation of the member.

3. A hydrant having, in combination, a main valve, an operating spindle for the 80 valve, a head, one or more hose nozzles supported on the head, mechanism for actuating the spindle, a hood inclosing the actuating mechanism and hose nozzles, a clamping ring on the head having flanges provided 85 with tapered lower faces, a rotary clamping member mounted in the hood and having feet arranged to engage with the tapered faces of the clamping ring upon rotation of the member.

4. A hydrant having, in combination, a 90 main valve, an operating spindle for the valve, a head, a plurality of hose nozzles supported on the head, mechanism for actuating the spindle, a hood inclosing the actuating mechanism and hose nozzles, a clamping ring having inturned flanges provided 95 with tapered lower faces, and a co-operating clamping member loosely supported in the hood and having outturned feet arranged to engage with the tapered faces of the clamping ring upon a rotation of the member.

5. A hydrant having, in combination, a main valve, an operating spindle for the 105 valve, a head, a plurality of hose nozzles supported upon the head, a plurality of guide pieces formed upon the head having vertical guideways formed therein, and a hood inclosing the nozzles and having ribs coöperating with the guideways to position 110 the hood accurately upon the head.

JOSEPH A. ROURKE.
